[57] CLAIM

The ornamental design for a telephone set, as shown
and described.

DESCRIPTION

FIG. 1 is a front, top and right side perspective view of
a telephone set showing my new design;

FIG. 2 is a top plan view thereof;

FIGS. 3 and 4 are respectively left and right side eleva-
tional views thereof;

FIGS. 5 and 6 are respectively front and rear eleva-
tional views thereof; and,

FIG. 7 is a bottom plan view thereof.

The showing of a fragmentary coiled cord connected
by a dash-dot line is for convenience of illustration and
to indicate cord continuity.
